UNITED STATES PATENT OFFICE.

WILLIAM TANKERSLEY, OF COLORADO SPRINGS, COLORADO, ASSIGNOR OF ONE-TENTH
TO HENRY SACHS, OF COLORADO SPRINGS, COLORADO, AND ONE-TENTH TO
DR. FRANK FINNEY, OF LA JUNTA, COLORADO.

WRENCH.

1,293,243.

Specification of Letters Patent.

Patented Feb. 4, 1919.

Application filed June 5, 1918. Serial No. 238,307.

To all whom it may concern:

Be it known that I, WILLIAM TANKERSLEY, a citizen of the United States, residing at Colorado Springs, in the county of El Paso 5 and State of Colorado, have invented certain new and useful Improvements in Wrenches, of which the following is a specification, reference being had to the accompanying drawings.

10 This invention relates to certain improvements in wrenches and it is an object of the invention to provide a novel and improved device of this general character which is so constructed as to especially adapt the same 15 for use in connection with motor driven vehicles and the like.

It is also an object of the invention to provide a novel and improved device of this 20 general character including a shank consisting of a plurality of sections connected for relative angular adjustment together with means for locking said sections in their various arrangements.

Another object of the invention is to provide 25 a novel and improved wrench including a shank consisting of relatively adjusted sections and wherein each of said sections is provided with a pair of work engaging jaws one movable relative to the other.

30 A still further object of the invention is to provide a novel and improved wrench including means whereby a lever or handle may be engaged therewith for increasing the purpose during the operation of the wrench 35 and wherein said lever or handle is also capable of use as a screw driver.

An additional object of the invention is 40 to provide a novel and improved wrench provided with an opening in the shank thereof through which a handle or lever is adapted to be disposed when it is desired to facilitate the rotation of the wrench about an axis disposed longitudinally thereof and wherein said handle or lever is provided 45 with a cross head engageable within the opening when it is desired to impart swinging movement to the shank.

The invention consists in the details of 50 construction and in the combination and arrangement of the several parts of my improved wrench whereby certain important

advantages are attained and the device rendered simpler, less expensive and otherwise more convenient and advantageous for use, as will be hereinafter more fully set forth. 55

The novel features of my invention will hereinafter be definitely claimed.

In order that my invention may be the better understood, I will now proceed to describe the same with reference to the accompanying drawings, wherein:

Figure 1 is a view partly in side elevation and partly in section of a wrench constructed in accordance with an embodiment 65 of my invention;

Fig. 2 is a view in edge elevation of my improved wrench as herein embodied, the coacting handle or lever being shown engaged therewith;

Fig. 3 is a view in side elevation of my 70 improved wrench with the sections thereof in folded relation and the handle or lever engaged therewith in a second position;

Fig. 4 is a sectional view taken substantially on the line 4—4 of Fig. 3; 75

Fig. 5 is a fragmentary longitudinal sectional view taken through my improved wrench as herein disclosed;

Fig. 6 is a sectional view taken substantially on the line 6—6 of Fig. 5; and 80

Fig. 7 is a sectional view taken substantially on the line 7—7 of Fig. 1.

As disclosed in the accompanying drawings S denotes the shank of my improved wrench which consists of two sections 1 and 85 2. The inner end of the section 1 is provided with a pair of transversely spaced wings or leaves 3 which extend beyond a face of the section 1 and which are substantially circular in contour and of equal radii. 90

Snugly fitting between the wings or leaves 3 is a substantially circular head 4 carried by the inner end of the section 2 and disposed through the axial center of the wings or leaves 3 and the head 4 is the pin 5 95 whereby the sections 1 and 2 are pivotally connected so that said sections may be angularly adjusted one relative to the other. The periphery of the head 4 terminates a material distance inwardly of the periphery of the wings or leaves 3 so that in practice the peripheral portion of the head 4 will 100

be protected and more particularly the outer or entrance ends of the recesses 6 produced in the periphery of said head.

The inner end of the section 2 at opposite

- 5 sides of the head 4 is provided with the inwardly directed ribs 7 which overlie the marginal portions of the wings or leaves 3 whereby said wings or leaves are materially reinforced during a working operation.
- 10 The face of the section 1 beyond which the wings or leaves 3 extend is provided with a longitudinally disposed recess or channel 8 open at the inner end of the section 1 and in which is mounted a slideable pawl 9. The outer end of the pawl 9 is slightly offset as at 10 in a direction away from the section 1 and terminates in the cross bar 11 which is adapted to enter within a pair of recesses 12 cut in the wings or
- 15 leaves 3 radially along the section 1. Intersecting the recess or channel 8 is a pin 14 which also extends through the slot 15 formed in the pawl 9. The slot 15 is of such length to permit the pawl 9 to slide 20 longitudinally of the recess or channel 8 but at the same time limits the rearward sliding movement thereof by contact of the end wall of said slot with the pin 14. The pin 14 also serves to maintain the pawl 9 in applied
- 25 position within the recess or channel 8. The recesses 12 are of such depth and the pin 14 is so positioned relative to the wings or leaves 3 to prevent complete withdrawal of the cross bar 11 from the recesses 12 so that
- 30 35 the pawl 9 is effectively held against accidental displacement. The pawl 9 can only be removed after the pin 14 has been withdrawn.

- The inner end of the pawl 9 is provided
- 40 with a lug 16 which affords a mounting for an end portion of a coil spring 17. The opposite end portion of the spring 17 is seated within a recess 18 formed in the inner end of the recess or channel 8. The spring 17
  - 45 constantly urges the pawl 9 toward the wings or leaves 3 so that the bar 11 will be received within the recess 6 when brought in register with the recesses 12 so that the sections 1 and 2 may be effectively locked in
  - 50 alignment or at different relative angles as occasioned by the requirements of practice and as permitted by the recesses 6.

- The outer end portion of the section 1 is provided with a pair of laterally directed jaws *a* and *b* one movable relative to the other and which project beyond the section 1 in the same general direction as the wings or leaves 3. The jaw *a* is fixed and forms a part of the head 19 and the jaw *b* is adjusted relative to the jaw *a* through the medium of the worm 20 rotatably supported within the recess or pocket 21 formed in the head 19 and coacting in a conventional manner with the threads 22 on the stem or shank 23 of the jaw *b*. It is to be noted that the

threads 22 are materially long which results in greater strength and with the possibility of the threads being stripped substantially entirely eliminated.

The outer end of the section 2 is also provided with a head 24 provided with the jaws *c* and *d* for relative movement transversely of the shank S and in a direction substantially at right angles to the direction of relative movement between the jaws *a* 75 and *b*. The jaws *c* and *d* also extend outwardly from the section S in a direction longitudinally of the section 1. The jaw *c* is stationary while the jaw *d* is adapted to be moved relative to the jaw *c* through the medium of the worm 25 in substantially the same manner as hereinbefore recited relative to the jaw *b*.

In practice it has been found of advantage to have the section 1 of a length substantially one-half the length of the section 2 and by this provision in conjunction with the pivotal connection between the sections 1 and 2 it is possible with my improved device to employ the same with particular convenience in connection with an automobile as it is possible to have ready access to the various nuts and bolts irrespective of the position of the workman. In order to facilitate the sliding movement of the pawl 9, the 85 opposite ends of the bar 11 are provided with the heads 27 having their outer surface roughened or knurled. The heads 27 serve as finger grips whereby movement of the pawl 9 against the action of the spring 17 90 is facilitated. The end portion of each of the heads 27 overlies the side face of the section 1 while the opposite end portion overlies a side face of the second section 95 when the sections are at the limit of their inward folding movement or substantially in parallelism. When the sections 1 and 2 are at the limit of their inward folding movement or substantially in parallel relation the jaws *a* and *b* are adapted to straddle the 100 section 2 whereby the sections 1 and 2 are effectively held against relative lateral movement and the head 19 and the jaws *a* and *b* carried thereby serve as a shield to protect the hand when the jaws *c* and *d* are used 105 and the sections 1 and 2 are folded.

Under certain conditions it is desired that the handle or lever L be employed for imparting the requisite turning or swinging movement to the shank S and for this purpose the section 1 adjacent the head 24 is provided with an opening 28 having the opposite ends thereof transversely enlarged or chamfered as indicated at 29. The handle or lever L is insertible through said opening when it is desired to rotate the shank about substantially its longitudinal axis and particularly when the jaws *a* and *b* are being used. By having the opposite end portions of the openings 28 transversely en- 115

larged or chamfered the removal of the handle or lever L or its equivalent is facilitated particularly in the event said handle or lever L should be bent during the working operation.

As herein disclosed one end portion of the handle or lever L is beveled as at 30 to permit its use as a screw driver so that said handle or lever L may have its individual function or duty. The opposite end portion of the handle or lever L is provided with a cross head C. Either arm 31 of the cross head C may be disposed through the opening 28 and the inner end portion of each of said arms is enlarged to fit within an end portion of the opening 28 so that the handle or lever L may be employed with convenience and facility for imparting the requisite swinging movement to the shank S particularly when the jaws c and d are engaged with the work. The recesses 6 have their side walls preferably parallel so that the sections 1 and 2 are effectively locked by the pawl 9 or more particularly the bar 11 carried thereby irrespective of the direction of the strain or stress imposed upon the shank S. It is also to be understood that the recesses 6 are to be of a number which best meets the requirements of practice and are herein disclosed as six in number. It is also to be noted that the wings or leaves 3 and the coacting head 4 are of such configuration as to permit a maximum swinging movement of the sections 1 of substantially 270°.

It has also been found of advantage to provide the bottom of the recess of channel 8 at the open end thereof with the outstanding rib 32 which partially closes the outer end of said recess or channel 8 and serves as a reinforcement and material aid in bracing the section 1 adjacent its pivotal connection.

The present application is filed as a substitute and partly in continuation of my application for Letters Patent filed May 15, 1917, Serial No. 168737, allowed January 26, 1918.

From the foregoing description, it is thought to be obvious that a wrench constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A wrench comprising a shank formed

from two straight sections, a hinge joint connecting the sections to permit the folding of the same in close parallel relation to each other or the adjustment thereof at intermediate angles, a spring held latch 70 carried by one of the sections for locking the hinge joint and having lateral extensions terminating in finger engaging heads projecting beyond opposite sides of the shank and adapted to overlap the sections thereof 75 when in close parallel relation to each other, and a jaw head on the outer end of one section and adapted to straddle the other section when both sections are in close parallel relation to each other.

2. A wrench comprising in combination, a shank consisting of two sections, a hinge joint therebetween to fold the sections one upon the other or at intermediate angles, one of the hinge joint members having a series of 85 recesses, a slideable pawl carried by one of the shank sections and resiliently pressed into engagement with a recess to positively hold the sections in one of their relative positions, finger grips carried by the pawl to 90 retract the slideable pawl to release the sections, said grips extending beyond opposite sides of the shank and overlapping the second shank section when the sections are in close folded relation, and wrench heads on 95 the free extremities of the sections.

3. In a foldable wrench, a shank element having a notched head at one end, a second shank element having spaced wings at one end between which the notched head is 100 mounted for pivotal movement, the second shank element having a channel therein, a pawl slidably mounted in the channel for movement into and out of position to engage in the notches of the head, the wings of the 105 second shank element having slots therein and in which the pawl is constantly seated, said pawl having finger grips lying outwardly of the wings of the second shank element, said grips overlapping the first shank element when both of the elements are in closely folded relation, a spring arranged to urge the pawl toward the head of the first shank element, and means for holding the pawl in applied position, said means also 110 serving to limit the movement of the pawl away from the head.

4. A wrench of the character described, comprising two shank sections, an end portion of one of the sections being provided 120 with spaced wings, an end portion of the second section being provided with a head insertible between the wings of the first section, means for pivotally connecting the wings and head, the periphery of the head terminating inwardly of the periphery of the wings, said head being provided with peripheral recesses, a pawl carried by the first section and coacting with the recesses 125 of the head for holding the sections against 130

4
movement about their pivotal connection, said pawl extending beyond opposite sides of the first shank section and overlapping the second shank section when both of said sections are in closely folded relation and webs carried by the second section and overlying the wings of the first named section.

In testimony whereof I hereunto affix my signature in the presence of two witnesses.

WILLIAM TANKERSLEY.

Witnesses:

MARIE RICKARDS,
HELEN J. COOK.
